ABSTRACT

Atopic allergic reactions, such as hives asthma, hay fever, allergic rhinitis, urticaria, conjunctivitis, food allergies, and the like, are prevented in a sensitive, warm-blooded animal by administration of a compound of the formula:

in which

R¹ is —H alkyl of 1 to 6 carbon atoms, alkoxy of 1 to 6 carbon atoms, hydroxyalkoxy of 2 to 6 carbon atoms, halo, —NO₂, —NH₂, dialkylamino having from 1 to 6 carbon atoms in each alkyl group, —CONH₂, —SO₂NH₂, carbalkoxy having from 2 to 6 carbon atoms or alkylthio of 1 to 6 carbon atoms; and

R² is —H, alkyl of 1 to 6 carbon atoms, an alkali metal cation or the ammonium cation, wherein the dotted line appearing in the structural formula represents optional unsaturation.

ISOQUINOLINECARBOXYLIC ACID
DERIVATIVES AS ANTI-ALLERGIC AGENTS

DESCRIPTION OF THE INVENTION

In accordance with this invention, there is provided a method for preventing the physical manifestations of atopic immediate sensitivity resulting from attacks of asthma, hay fever, allergic rhinitis, urticaria, conjunctivitis, food allergies, and the like, in warm-blooded animals, which comprises administering to a sensitized mammal at least one compound of the formula:

in which

R¹ is —H, alkyl of 1 to 6 carbon atoms, alkoxy of 1 to 6 carbon atoms, hydroxalkoxy of 2 to 6 carbon atoms, halo, —NO₂, —NH₂, dialkylamino having from 1 to 6 carbon atoms in each alkyl group, —CONH₂, —SO₂NH₂, carbalkoxy having from 2 to 6 carbon atoms or alkylthio of 1 to 6 carbon atoms; and

R² is —H, alkyl of 1 to 6 carbon atoms, an alkali metal cation or the ammonium cation, wherein the dotted line appearing in the structural formula represents optional unsaturation.

The preferred anti-allergics of this invention from the standpoint of production economics and pharmacological activity levels present the structural formula:

in which

R¹ is —H or alkoxy of 1 to 6 carbon atoms; and
R² is —H, alkyl of 1 to 6 carbon atoms or an alkali metal cation,

wherein the dotted line appearing in the structural formula represents optional unsaturation.

In addition, there is provided by this invention, certain novel anti-allergic compounds of the formula:

in which

R¹ is alkyl of 1 to 6 carbon atoms; and
R² is —H, alkyl of 1 to 6 carbon atoms, an alkali metal cation or the ammonium cation.

5 Atopic hypersensitivity, as found typically in man, dog and other higher mammals, occurs exceptionally in the lower animals, and is most frequently caused by inhalation or ingestion of substances such as plant pollen, animal feathers and danders, dust, milk, wheat and similar poisons or irritants.

The presence of antibodies associated with atopic reactions in the host serum is established by passive sensitization of the skin of a normal recipient, after injection of serum from a sensitized host into a skin site followed by injection of antigen into the same skin area twenty four hours later, producing a local hive. This is commonly referred to as the Prausnitz-Kustner (P-K) reaction.

20 The antibody associated with atopic hypersensitivity possesses distinctive features in that it does not in all forms precipitate with its antigen, fails to pass the placenta from mother to fetus, has special affinity for the skin, frequently lacks specificity toward an individual antigenic factor and is usually labile at about 56°C. after two hours.

25 The homocytotropic antibody found in or induced in the rat is related in function and reaction to immunoglobulin E (reagin or IgE) found in the human. The functional correlation between homocytotropic antibody in the rat and IgE in the human has been established through their common effects obtained from chemical reactions, immunological reactions and drug responses in the two species hosting those antibodies.

30 In the human, reagin is the antibody responsible for atopic immediate hypersensitive reactions, while homocytotropic antibody is the corresponding antibody in the rat responsible for atopic immediate hypersensitive reactions. Based upon the functional correlation between the homocytotropic antibody in the rat, similar antibodies in the dog, and IgE in the human, effects obtained in the rat as the standard experimental animal are extrapolatable to higher animals such as the dog and man.

35 In theory, reagin influences the cell membrane of a mast cell by reacting with an antigen to initiate the reaction(s) within the mast cell which ultimately releases a mediator such as Bradykinin, SRS-A (slow reacting substance-A), histamine and other unknown substances. The mediator effects a change in surrounding cell wall permeability permitting a rapid change in flow or exudance of mediator(s) from the cells, resulting in an allergic attack symptom. Various methods are commonly employed to relieve the symptoms of allergic attack, none of which are quite acceptable, including

40 (1) avoid the attack by the antigen, (2) block the production of antibody with an immunosuppressant, (3) block the action of the mediators on the cell under attack by administration of anti-histaminics, anti-5-hydroxy tryptamine (5-HT) or antiinflammatories or (4) stimulate the cell under attack to negate the action of the mediator through the action of bronchodilators such as Isoprel or a Xanthine.

45 Although the specific type of activity elicited from administration of 1-oxo-3-isoquinoline carboxylic acid derivatives as herein disclosed is not known, it is believed that the reaction(s) within the mast cells are blocked, thereby preventing production and release of

mediators, in a manner similar to the activity of IN-TAL, which permits the occurrence of non-productive antigenantibody interaction in the mast cell without formation of mediators.

In practice, the 1-oxo-3-isoquinolinecarboxylic acid derivatives are administered parenterally to the sensitized animal prior to an allergic attack in an amount necessary to obtain the desired response, whether partial or complete relief is desired, in single or plural doses initially under the guidance of medical assistance for the purpose of determining the optimum dosage for the specific animal being treated. The effective dose range in test animals is between about 5 to 200 milligrams per kilogram within which range, the dose-response curve favors treatment with from about 5 to about 100 milligrams per kilogram host body weight. Thus, for veterinary use, such as in the dog, the size of the specific animal being treated dictates the proper dose size. If desired, the compounds of this invention may be administered in conjunction with known compounds effecting antihistaminic, anti-hypertensive, analgesic, central nervous system depressant, immunosuppressive, anti-serotonin, anti-Bradykinin or endocrinological responses. In addition, those conventional adjuvants known to the art may be combined with the anti-allergics of this invention to provide compositions and solutions for administrative purposes, although it is considered desirable and feasible to employ the anti-allergics as neat or pure compounds without additives other than for purposes of providing suitable pharmaceutical solution or liquid or vapor suspensions.

The 1,2-dihydro and 1,2,3,4-tetrahydro-1-oxo-3-isoquinolinecarboxylic acid derivatives are produced by known methods. Thus, for example, an appropriate ring substituted 2-carbomethoxy benzaldehyde

in which R¹ is defined above, is condensed with hippuric acid in the presence of sodium acetate and acetic anhydride to obtain 2-phenyl-4-substituted-o-carbomethoxybenzylideneoxazolone

which yields 1,2-dihydro-1-oxo-3-isoquinolinecarboxylic acid upon treatment with potassium hydroxide. The

free carboxylic acid is converted to an ester or salt by conventional methods. If desired, the group R¹ may be introduced as a ring substituent after the 1,2-dihydro-1-oxo-3-isoquinoline ring is formed, by carrying an appropriately reactive group through the ring closure in the illustrated 8-position (or the desired position) for the subsequent substitution reaction.

The 1,2,3,4-tetrahydro-1-oxo-3-isoquinoline carboxylic acid derivatives are produced by esterification of phenylalanine, conversion of the amino group to an isocyanato group with phosgene in the presence of an acid acceptor and ring closure with aluminum chloride. The aromatic ring substituent R¹ may be present during the ring closure or introduced subsequently by known methods.

EXAMPLE 1

1,2-Dihydro-1-Oxo-3-Isoquinolinecarboxylic Acid Sodium Salt

This compound is known in the chemical literature and is prepared by the method of: D. Bain, W. H. Perkin and R. Robinson, J. Chem. Soc., 105, 2392 (1914). The sodium salt is prepared from the acid (2.72 g., 0.0144 mole) by addition of 14.40 ml. of 1.000 N sodium hydroxide to a suspension of the acid in 75 ml. water. The solution is filtered and the filtrate is freeze dried, giving 3.1 g. of the salt, mp. > 300° C.

Analysis for: C₁₀H₆NNaO₃. 0.85H₂O. Calculated: C, 53.0; H, 3.42; N, 6.18; H₂O, 6.80. Found: C, 52.57; H, 2.97; N, 6.85; H₂O, 6.05.

Sodium 1,2-dihydro-1-oxo-3-isoquinolinecarboxylate was administered intraperitoneally at a dose of 200 milligrams per kilogram body weight to each of four male Charles River rats (200-250 grams body weight) which had been treated twenty four hours earlier by intracutaneous injection of sera from rats immunized with egg albumin and pertussis vaccine. Five minutes later, one milliliter of a 0.5 percent solution of Evans blue dye and eight milligrams of egg albumin were introduced intravenously to each animal. After forty minutes the bleb size formed at the skin site of the prior intracutaneous injection was measured. The mean bleb size for the four animals demonstrated a reduction of 60 percent over that of a four rat control group simultaneously treated in the same manner except for administration of the anti-allergic compound.

EXAMPLE 2

1,2,3,4-Tetrahydro-1-Oxo-3-Isoquinolinecarboxylic Acid, Methyl Ester

This compound is known in the chemical literature and is prepared by the method of S. Cohen and R. Schultz, J. Biol. Chem., 243, (10), 2607-2617 (1968).

Following the identical procedure of the preceding example, methyl 1,2,3,4-tetrahydro-1-oxo-3-isoquinolinecarboxylate was administered to four male Charles River rats, resulting in a 76 percent inhibition of bleb size in comparison to the control group.

EXAMPLE 3

8-Methoxy-1,2-Dihydro-1-Oxo-3-Isoquinolinecarboxylic Acid

The appropriate phthalaldehydic acid ester is in the literature: F. Bohlmann and K. Prezewowsky, Chem. Ber., 97, 1178 (1964).

This ester is condensed with hippuric acid and hydrolyzed to the desired compound as in Example 1.

The anti-allergic activity of the title compound is elicited by administration in accordance with Example 1.

EXAMPLE 4

8-Ethoxy-1,2-Dihydro-1-Oxo-3-Isoquinolinecarboxylic Acid

2-Bromo-m-cresol is alkylated using diethyl sulfatesodium hydroxide. This ethyl ether is then converted to the phthalaldehydic ester by the method of Eliel, et al., J. Org. Chem., 18, 1684 (1953).

The isoquinoline is prepared as in Example 1.

The anti-allergic activity of the title compound is elicited by administration in accordance with Example 1.

What is claimed is:

1. A method for preventing the physical manifestations of an atopic allergic reaction which comprises parenterally administering to a warm-blooded animal in need thereof, an effective amount of a compound of the formula:

in which

R¹ is —H, alkyl of 1 to 6 carbon atoms, alkoxy of 1 to 6 carbon atoms, hydroxyalkoxy of 2 to 6 carbon atoms, halo, —NO₂, —NH₂, dialkylamino having from 1 to 6 carbon atoms in each alkyl group, —COHN₂, —SO₂NH₂, carbalkoxy having from 2 to

6 carbon atoms or alkylthio of 1 to 6 carbon atoms; and

R² is —H, alkyl of 1 to 6 carbon atoms, an alkali metal cation or the ammonium cation, wherein the dotted line appearing in the structural formula represents optional unsaturation.

5 2. The method of claim 1 which comprises parenterally administering to said warm-blooded animal, an effective amount of a compound of the formula:

in which

R¹ is —H or alkoxy of 1 to 6 carbon atoms; and

R² is —H, alkyl of 1 to 6 carbon atoms or an alkali metal cation,

25 wherein the dotted line appearing in the structural formula represents optional unsaturation.

3. The method of claim 1 which comprises administering to said warm-blooded animal the compound 1,2-dihydro-1-oxo-3-isoquinolinecarboxylic acid.

4. The method of claim 1 which comprises administering to said warm-blooded animal to compound sodium 1,2-dihydro-1-oxo-3-isoquinolinecarboxylate.

35 5. The method of claim 1 which comprises administering to said warm-blooded animal the compound methyl 1,2,3,4-tetrahydro-1-oxo-3-isoquinolinecarboxylate.

6. The method of claim 1 which comprises administering to said warm-blooded animal the compound 40 8-methoxy-1,2-dihydro-1-oxo-3-isoquinolinecarboxylic acid.

7. The method of claim 1 which comprises administering to said warm-blooded animal the compound 45 8-ethoxy-1,2-dihydro-1-oxo-3-isoquinolinecarboxylic acid.
